SOLDERING IRON STAND

Joseph A. Sylvester, Wayne, N.J., assignor to Hexacon
Electric Company

Continuation-in-part of design application Ser. No. 19,989,
Nov. 10, 1968. This application Nov. 6, 1970, Ser.
No. 25,975

Term of patent 14 years

Int. Cl. D8—05

U.S. Cl. D8—71

FIG. 1**FIG. 2****FIG. 3**FIG. 4

FIG. 5

FIG. 6

FIG. 7

FIG. 8

FIG. 9

FIG. 1 is a right side elevational view of the soldering iron stand;

FIG. 2 is a top plan view;

FIG. 3 is a rear elevational view;

FIG. 4 is a left side elevational view;

FIG. 5 is a bottom plan view;

FIG. 6 is a front elevational view thereof;

FIG. 7 is a perspective top view of FIG. 2 excluding the spring and mount therefor;

FIG. 8 is a top plan view of a second embodiment of the design;

FIG. 9 is a top plan view of FIG. 8 excluding the spring and mount therefor.

This application is a continuation in part of my pending application D.19,989 filed Nov. 10, 1969, now abandoned.

I claim:

The ornamental design for a soldering iron stand, as shown and described.
